UNITED STATES PATENT OFFICE.

JOSEPH FRANCIS, OF WESTMINSTER, LONDON, ENGLAND.

CLIP FOR METALLIC LATHING.

No. 927,137.

Specification of Letters Patent.

Patented July 6, 1909.

Application filed July 29, 1908. Serial No. 445,932.

To all whom it may concern:

Be it known that I, JOSEPH FRANCIS, M. Inst. C. E., a subject of the King of Great Britain and Ireland, residing at 28 Victoria street, Westminster, London, England, have invented certain new and useful Improvements in Clips for Metallic Lathing, of which the following is a specification.

This invention relates to clips for use in securing to the flanges of joists, girders or columns, wire netting, expanded metal or like materials commonly used to form a key for cement or plastering or for analogous purposes.

15 The clip is in the form of a bar or strip of iron or other malleable material having a hook at one or both ends and of such a length that it can embrace one flange of the joist or girder. The body of the clip before application may be straight or bent up at the end or ends. To apply it to the joist the ends are bent, by hammering or pressing, over the top of the flange and grip it tightly. The wire netting or other keying material is then engaged by the hooked ends and so held across the face of the joist ready to receive the cement or plastering. The hook may be closed to secure the netting more efficiently.

20 In order that my invention may be more readily understood, reference is had to the accompanying sheet of drawings in which:—

Figure 1 shows in section the bottom flange of a joist or girder with one form of my improved clip upon it; Fig. 2 is a similar view before the netting is secured and with a slightly modified form of clip; and Figs. 3 and 4 show other forms of clip employed in the manner shown in Fig. 5.

25 Referring to Fig. 1 A is the bar of wrought iron, mild steel or other ductile material which, before application to the joist B, is made with bent up ends *a* having the engaging hooks *a*¹ at their extremities. The middle part is of a length corresponding to the flange of the joist and in applying the clip it is held against the flange with the ends *a* projecting at about right angles as shown in dotted lines, whereupon these ends are bent down by hammering or other means upon the upper face of the flange so that the latter is embraced and firmly gripped. The wire netting or other keying material C is then engaged in one hook *a*, stretched over the bottom of the flange and engaged in the second hook. The hooks may then be closed in the form of a loop as shown in Fig. 1 to give

greater security to the material, which may be stretched tightly or loosely as found desirable.

30 In Fig. 2 the clip is shown in full lines in position ready for use, but the original shape of the clip differs slightly from that in Fig. 1, the end *a*² being already bent to the shape of the flange while the opposition end *a*³ is a straight continuation of the central part of the bar. This form permits the clip to be slipped over one edge of the flange and to be secured by hammering or pressing over one end only.

35 The figures described above show the clip applied to the bottom flange of a horizontal joist used for the construction of floors, with the material C (Fig. 1) forming a key for the ceiling plaster, but I may also use a clip of this type for vertical or other columns which are to be cased in concrete or plaster. This application of the clip is shown in Fig. 5 and two types of clip are shown before use in Figs. 3 and 4. Fig. 3 shows the clip A¹ in the form of a straight bar with a hook *a*¹ at one end only, while in Fig. 4 the other end *a*⁴ is bent to slip over the flange of the column B¹ and only one end requires to be bent over in applying the clip. The complete clip A¹ when secured provides a hook at one side of the column and the keying material C¹ is engaged with the hook *a*¹ at one edge, drawn completely around the column and then engaged with the same hook at its other edge, inclosing the column in the manner illustrated. The hook can then be closed over both edges of C¹ with a hammer. As the keying or lathing material is of such well known character as wire netting, expanded metal and the like, its section has been merely shown diagrammatically in Figs. 1 and 2 by the dotted lines at C and C'.

40 With clips of this type the labor involved in securing the netting or other material employed is greatly reduced, as the application of the clip is a very simple operation and can be effected rapidly.

45 What I claim as my invention and desire to secure by Letters Patent is:—

50 1. A clip for securing flexible lathing material to joists, columns and the like, consisting of a strip of malleable metal adapted to extend across the face of the joist flange, having bent ends engaging over the upper sides of the flange and an inwardly opening hook at the extremity, on to which the lathing material is hooked, which hook is formed

by bending back the material of the metal strip, substantially as and for the purpose herein described.

2. A clip for securing flexible lathing material to metal joists, columns and the like consisting of a strip of malleable metal bent at both ends to embrace a flange of the joist or column and an inwardly opening hook at each extremity, lying upon the inner side of the flange, formed by bending back the ma-

terial of the metal strip and adapted to hook the lathing material at each side, substantially as and for the purposes herein described.

In witness whereof I have hereunto set my hand in the presence of two witnesses.

JOSEPH FRANCIS.
